US0D1094523S

(12) **United States Design Patent** (10) **Patent No.:** **US D1,094,523 S**
(45) **Date of Patent:** **** Sep. 23, 2025**

(54) **SUPPORT FOR TERMINALS**

(71) Applicant: **SHENZHEN DIEPIN TECHNOLOGY CO., LTD.**, Shenzhen (CN)

(72) Inventor: **Weihao Chen**, Shenzhen (CN)

(73) Assignee: **SHENZHEN DIEPIN TECHNOLOGY CO., LTD.**, Shenzhen (CN)

(**) Term: **15 Years**

(21) Appl. No.: **29/908,127**

(22) Filed: **Jan. 11, 2024**

(30) **Foreign Application Priority Data**

Nov. 13, 2023 (CN) 202330739105.9
(51) **LOC (15) Cl.** **14-06**
(52) **U.S. Cl.** ..... **USPC** **D14/253; D16/242**
(58) **Field of Classification Search**
USPC D16/237, 242-245; D14/253
CPC G03B 17/56; G03B 17/561

(57) **CLAIM**

The ornamental design for a support for terminals as shown and described.

DESCRIPTION

FIG. 1 is a front right side perspective view of a support for terminals showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a change state view thereof.

1 Claim, 8 Drawing Sheets
